UNITED STATES PATENT OFFICE.

GUSTAVE A. HENCKEL, OF SOUTH ORANGE, NEW JERSEY.

DESIGN FOR A CIGAR AND CIGARETTE CASE.

44,128.

Specification for Design.

Patented June 3, 1913.

Application filed March 29, 1913. Serial No. 757,711. Term of patent 14 years.

To all whom it may concern:

Be it known that I, GUSTAVE A. HENCKEL, a citizen of the United States of America, residing in South Orange, in the county of Essex and State of New Jersey, have invented a new, original, and ornamental Design for a Cigar or Cigarette Case, of which the following is a specification, reference being had to the accompanying drawing, forming part thereof.

The figure shows a design for a cigar and cigarette case.

I claim:

The ornamental design for a cigar and cigarette case, as shown.

In testimony whereof I have signed this specification in the presence of two subscribing witnesses.

GUSTAVE A. HENCKEL.

Witnesses:

H. M. MARBLE,
PAUL H. FRANKE.
